UNITED STATES PATENT OFFICE.

BENJAMIN C. BARTLEBAUGH, OF WHEELING, WEST VIRGINIA.

GAS-FURNACE.

1,110,867.

Specification of Letters Patent. Patented Sept. 15, 1914.

Application filed May 11, 1914. Serial No. 837,916.

To all whom it may concern:

Be it known that I, BENJAMIN C. BARTLEBAUGH, a citizen of the United States, residing at Wheeling, in the county of Ohio and State of West Virginia, have invented new and useful Improvements in Gas-Furnaces, of which the following is a specification.

The present invention relates to gas furnaces, and it proposes, briefly, an article of manufacture of the general class or character specified having a plurality of improved, internal channels wherein the gas is burned and through which the super-heated air rapidly circulates in a continuous or closed path. The construction and arrangement of these channels are such that the ascending column of heated air exerts a suction action within the channel through which the flame and products of combustion travel, and thereby draws any unburned gases with it into a return channel, whence the mixture of air and gas is driven across the burner, so that a maximum degree of consumption and heating is insured.

An embodiment of the invention is illustrated in the accompanying drawing, whereof:

Figure 1 is a perspective view of the improved furnace; Fig. 2 is a horizontal section on line 2—2, Fig. 3; and Fig. 3 is a vertical section on line 3—3, Fig. 2.

Referring to said drawing, 5 indicates, generally, the casing of the furnace, and 6 the burner. The first of these elements may be of any approved form, or design. In the embodiment shown, it is of rectangular outline, and it has the lower portions of its front wall 5' cut away to provide an opening 7 for the admission of air and for the escape of the products of complete combustion.

Within the casing or furnace, and disposed in spaced, parallel relation to the front wall 5' is a partition wall 5⁸ which terminates short of the top wall 5⁴ at its upper end and is provided at such point with a rearwardly-projecting horizontal extension or flange 5⁵ that is similarly arranged with respect to said wall 5⁴ and, in like manner, terminates short of the back wall 5². Finally, there is a second partition wall 5⁶ arranged interiorly of the furnace, but this wall, instead of being arranged in a truly vertical plane, has a forward and upward inclination, terminating below and in spaced relation to that of the extension

wall or flange 5⁵. The lower end of wall 5⁶ extends a slight distance below that of wall 5³ and is formed with a forwardly-projecting offset or shelf 5⁷ which, in turn, is continued forwardly and downwardly at 5⁸ to form the front wall of a chamber 8 having a closed bottom 5¹⁰, the said wall 5⁸ being provided adjacent its upper end, with a horizontal series of perforations 5⁹. The several internal walls or partitions 5³, 5⁵, 5⁶, 5⁷, 5⁸ and 5¹⁰, extend the entire width of the furnace, the wall 5⁷ serving to support a block 9 of refractory material, over which and upwardly along the front face of wall 5⁶ for a suitable distance extends a layer of mineral wool 10.

The burner 6 is located in front of wall 5⁸ and slightly below the perforations 5⁹ therein, and it is likewise coextensive with the furnace. It is here shown as constituted by an elongated, horizontally-arranged cylinder, the upper side of which is provided with small, closely-associated outlet perforations for the gas, the latter being supplied from a pipe 6' that is connected at its discharge end to a suitable mixer 6² that, in turn, opens through the central portion of the lower side of the burner.

The arrangement of the furnace walls are such that three separate vertical channels 11, 12 and 13 are produced thereby, as will now be explained. These channels are disposed one in front of another, the first or front channel being that between the walls 5' and 5³, the second or intermediate channel being the one between the walls 5³ and 5⁶, and the third or rear channel being the one between the walls 5⁶ and 5². The front and intermediate channels communicate at 95 their upper ends with the corresponding end of the rear channel, the former of the two channels just mentioned having its connection effected through the agency of the auxiliary channel 11', produced between the walls 5⁴ and 5⁵. The lower end of the channel 13 opens into the chamber 8, while the corresponding end of the channel 12 is situated directly above the burner.

As a result of this arrangement, the air 105 entering the furnace through the opening 7 crosses the jets or flame at the burner, is heated thereby, and then passes up through the channel 11, while the products of combustion, together with any unburned gases, 110 pass, in like manner, into and through the intermediate channel 12, the flame likewise

entering the latter channel. On reaching the top of channel 11, the air current passes into and through the branch channel 11', and then enters the rear channel 13, crossing the outlet of channel 12 at such point, and as it passes said outlet, it becomes mixed with the unburned gases and products of combustion and carries the same with it through channel 13, this mixing of the unburned gases and products of combustion with the heated air being due partly to the natural upward flow of the former and partly to the suction action exerted in the channel 12 by the air current as it passes across the mouth of the aforesaid channel. On arriving at the bottom of channel 13, the mixture enters the chamber 8, whence it is then forced, jet-like, through the perforations 5° and across the flame, where the combustible gases and any other unburned combustible substances are consumed, the air being re-heated and passing again into the channel 12. In this way, a continuous circulation and constant re-heating are provided for, and total consumption of gas insured, the products of complete combustion escaping through the opening 7. Also, since the channels are comparatively large, the heating will take place rapidly, and a maximum quantity of heat will, in consequence, be given off.

I claim:-

1. A gas furnace having open-ended internal, vertical air and flame channels arranged one in front of the other, and an internal, vertical mixing channel arranged behind the flame channel and with which the latter channel and the air channel communicate at their upper ends; and a burner arranged beneath the lower end of said flame channel, the lower end of the mixing channel being in communication with the burner space directly adjacent the flame, whereby the gaseous mixture will be discharged from the said mixing channel directly into the flame.

2. A gas furnace having internal, front, intermediate and rear vertical channels in communication at their upper ends; and a burner located beneath the lower end of the intermediate channel, the rear channel ex-

tending below the intermediate and front channels and communicating with the burner space directly opposite the burner apertures.

3. A gas furnace partitioned internally to produce vertical air, flame and mixing channels arranged successively from front to back thereof, the partition between the air and flame channels having a horizontal, rearwardly extending offset at its upper end which terminates in spaced relation to the rear wall of the furnace and to the upper end of the partition between the flame and mixing channels; and a burner arranged beneath the lower end of the flame channel, the last-named partition having a depending extension which is arranged behind and projects below said burner and is provided with a series of perforations disposed opposite the burner apertures, whereby the gaseous mixture descending through the mixing chamber will be discharged through said perforations directly into the flame.

4. A gas furnace provided with an inlet opening at the lower front portion thereof and having open-ended internal, vertical air and flame channels arranged one in front of the other and above said opening, the air channel having its lower end located directly adjacent said opening and having its upper end laterally offset and communicating with that of the flame channel, and an internal, vertical channel arranged behind the flame channel, with which the upper ends of the latter and the air channel communicate; and a burner arranged beneath the lower end of said flame channel, the lower end of the mixing channel communicating with the burner space directly adjacent the flame, whereby the gaseous mixture will be discharged from said mixing channel directly into the flame.

In testimony whereof I have hereunto set my hand in presence of two subscribing witnesses.

BENJAMIN C. BARTLEBAUGH.
